Army

Application August 14, 1950; Serial No. 179,334

2 Claims. (Cl. 74—527)

1

The present application is related to Patent No. 2,479,465, dated August 16, 1949, issued in the name of the present applicants and assigned to the Bell Telephone Laboratories, Inc., in that the claims herein are claims cancelled, pursuant to a requirement of division, from the application filed January 4, 1947, Serial Number 720,222, which matured into the patent referred to above.

This invention relates to control devices and more particularly to control devices operable to control a plurality of rotatable members such for instance as the motor shafts of a plurality of variable electrical devices.

An object of the invention is to provide an improved control apparatus by means of which a plurality of rotatable shafts may be differently affected and in accordance with a required program by selecting and operating a control member.

The invention feature resides in a releasable detent means.

In the drawings:

Fig. 1 is a view, in perspective, of a control apparatus embodying the invention and shows the front of a casing-type body;

Fig. 2 is a plan view showing the underside of the slidable member.

In apparatus involving a plurality of rotatable members required to be rotated to different extents to condition the apparatus for certain requirements it is common practice to provide a separate means for facilitating the rotation of each rotatable member required to be rotated. In such cases several operations are required to condition the apparatus to meet the requirements since each rotatable member must be separately operated. To reduce the number of operations required to rotate a plurality of rotatable members the rotatable members are in some cases arranged for operation by means of a single rotatable shaft common to the plurality of rotatable members, mechanical drives being provided between the single shaft and the rotatable members. When the single shaft is rotated all of the rotatable members in mechanical driving connection therewith are rotated. In some cases the structures and arrangements of the various parts are such that the rotatable members are rotated in different ratios of movement, the ratios of movement are fixed, however, and the same ratios prevail under all rotative movements applied to the parts.

In the present invention the control device may be operated to cause a plurality of rotatable shafts to be operated at different ratios or affected in different manners by suitable selection and operation of a rotatable member in the control device.

As shown in Fig. 1 the control device 10 comprises a casing type body 11 having an apertured

2

front wall 12 and an apertured rear cover plate 13. Extending through the front wall 12 and the rear cover plate 13 are rotatable shafts 14 and 15 which may be equipped with turnable knobs (not shown) to facilitate rotation of the shafts 14 and 15.

Detent means 20 and 21, shown in Fig. 1, are provided to normally hold the shafts 14 and 15, respectively in required adjusted positions and aid an operator in rotating the shafts 14 and 15 in definite required step-by-step rotational movements. The detent means 20 comprises a set of spaced studs 22 and a latch means 23 having a slidable member 24 operable to selectively engage the studs 22. The studs 22 are arcuately arranged and mounted on a cup-type support 25 arranged outside the body 11 and extend normal to the front face of the body 11. The slidable member 24 is frame-like in form and is slidably supported in a mounting 26 which is channel-shaped in cross-section and has an apertured boss portion 27 extending from a block portion 28 formed on a base wall 29 of the mounting 26. The apertured boss portion 27 is apertured to accommodate the shaft 14 and is secured to the shaft 14 by a set screw or other suitable securing means, not shown. A retainer bar 30 secured by suitable securing means 31 to the block portion 28 of the mounting 26 extends in overlapping relation with side walls 32—32 of the slidable member 24 to retain the slidable member 24 in the mounting 26. Integral with the block portion 28 and extending from the boss portion 27 to one end of the mounting 26 is a hollow cylindrical portion 33 in the bore of which is enclosed a helical spring 34 providing a pressure member for a plunger 35 one end of which bears against the inner edge of an end wall 36 of the slidable member 24, the other end of the plunger 35 being in engagement with an outer end of the helical spring 34. The outer end portion of the end wall 35 of the slidable member 24 is tapered in form and the outer end is recessed and cut through at the base of the recess as shown at 37 to fit partly around a stud 22. The function of the helical spring 34 and the plunger 35 is to constantly urge the slidable member 24 lengthwise of the mounting 26. When the shaft 14 is rotating relative to the cup-type support 25 and the outer end 36 of the slidable member 24 comes into engagement with a stud 22 the slidable member 24 is pressed inwardly toward the shaft 14 and against the action of the spring 34 by reason of the engagement of the outer end 36 with a stud 22. The inward pressure is continued until the recess 37 comes into register with the stud 22 at which point the stud 22 fits into the recess 37 and has a tendency to stop rotation of the shaft 14. Since the outer

end 36 of the slidable member 24 is cut through at the base of the recess as shown at 37 the outer end 36 comprises two half portions separated by an opening. The two half portions may be slightly sprung apart. The slidable member 24 and the engaged stud 22 cooperate to tightly latch the shaft 14 against free movement and operate as a detent for the shaft 14. As the recess in the outer end 36 comes into register with a stud the pressure of the slidable member 24 against stud 22 forces the two halves of member 24 apart until all clearances against mounting 26 are eliminated. The detent means 21 for the shaft 15 is constructed somewhat along the general lines of the detent means 20 but does not have the cup-type body 25. A releasable holding means 38 is provided to hold the slidable member 24 from engagement with the studs 39 at required times when free rotation of the shaft 15 is required. The studs 39 correspond in general to the studs 22 but are mounted in spaced relation on a generally semicircular boss 40 on the outer face of the body 11. The detent means 20 and 21 and their particular manners of operation will be subsequently more fully explained.

Referring particularly to Figs. 1 and 2 the detent means 21 for the shaft 15 does not have the cup-type support 25, the studs 39 being mounted on a boss 40 on the wall 12 of the body 11. A releasable holding means 38 is provided to withdraw and hold the slidable member 128 from engagement with the studs 39. The slidable member 128 except for the inclusion therein of a pin 129 is constructed similar to the slidable member 24 in the detent means 20. Extending through the mounting 26 is a pin 132 between shaft 15 and pin 129. Pivotaly mounted about the pin 132 and on the underside of mounting 26 is a V-shaped latch 130 having legs 134 and 135, the inner periphery of said legs forming a crotch that receives pin 129 when slidable member is in engageable detent position. Along the inner edge of leg 134, a short distance from the apex of the crotch is a notch 136. Latch 130 is spring loaded by means of a spring 133, having one end secured to the frame by any convenient means and extending to and wrapped about the pin 132, the other end terminating on the leg 134 whereby latch 130, as shown in Fig. 1, is normally urged in a clockwise direction. A short distance from the terminal portion 151 of boss 40, as shown in Fig. 1, is a lever 131 one end of which is mounted about a pin (not shown) extending into the wall 12. The other end of lever 131 is held by a spring 153, which normally urges lever 131 in a clockwise direction, the other end of said spring 153 being held by a bolt which is spaced from the lever and extends into the wall 12. Adjacent to the other terminus of boss 40 is a post 139 affixed to front wall 12.

In operation, as stated above, when pin 129 is within the crotch of latch 130, the slidable member 128 is in engageable detent position with any one of the studs 39. When member 128 is moved in an arcuate path from stud to stud by rotation of shaft 15, as tapered portion 36 rides over the circumference of the studs, member 128 is urged in a direction away from the studs. Upon rotating shaft 15 counterclockwise, as depicted in Fig. 1, so that member 128 is moved beyond the last stud 39, pin 129 hits lever 131 preventing further movement of said pin. Spring 153 of lever 131 serves to cushion lever 131 against the impact. Latch 130 meanwhile rides over the lever 131 and

pivots slightly as a result of inertia force produced by the impact of pin 129 against lever 131. This permits pin 129 to ride partially into notch 136. Latch 130 now being free to move is snapped in a clockwise direction by spring 133, the pin thereby being completely received in the notch. By this arrangement, slidable member 128 is locked in retracted or off detent position.

To release the slidable member 128 from its locked position to an engageable position, shaft 15 is rotated to move member 128 to the extreme clockwise position, as in Fig. 1. At this point, leg 134 of latch 130 strikes fixed post 139. The sudden impact causes latch 130 to rotate sufficiently counterclockwise to permit pin 129 to move out of notch 136 into the crotch portion of the latch, thereby placing the slidable member into engageable detent position. This control device may be arranged so that when shaft 15 is rotated over all of its detent studs 39, shaft 14 with its cup-type support 25 and detent studs 22 will rotate nine-tenths of the distance between two detent studs 22. In order that the proper index may be read directly an indexing mask 137 is fastened to the cup-type support 25 so as to block out adjacent indexes.

This control device contains a ready interchangeable feature where several similar cup-type supports 25 containing different numbers of detent studs 22 may be interchanged by inserting in required relation with its respective rocker arm 42 which connects shafts 14 and 15 as shown in applicant's Patent No. 2,479,465. Maximum flexibility is obtained by changing the shaft location of the rocker arm 42 without changing the other gears in the device or the decimal relation of shaft 15 to shaft 14.

What is claimed is:

1. A control device comprising an apertured support, a shaft rotatably supported in said support, spaced studs arranged relative to said shaft, an apertured body secured to said shaft, a slidable member supported in said body and slidable therein and operable to selectively engage said studs, a recessed and cutthrough end portion on said slidable member to engage said studs and slightly spread apart, upon engagement with said studs when the recess is in register with a stud, and plunger means supported in said body and operable to urge said slidable member into engagement with said studs.

2. A control device comprising an apertured support, a shaft rotatably supported in said support, spaced studs arranged relative to said shaft, means supporting said studs, an apertured channel type body secured to said shaft, a slidable member supported in said channel type body and operable to selectively engage said studs, spring means supported in said channel type body and operable to urge said slidable member into engagement with said studs and releasable holding means for said slidable member operable to withdraw and hold said slidable member from engagement with said studs.
